UNITED STATES PATENT OFFICE

2,410,718

STOP MOTION FOR KNITTING MACHINES

Alfred Crawford, New Brunswick, N. J., assignor
to Crawford Manufacturing Company, New
Brunswick, N. J., a corporation of New Jersey

Application January 30, 1946, Serial No. 644,288

4 Claims. (Cl. 66—163)

1

This invention relates to improvements in stop motions for knitting machines and more particularly to improvements specific to the type of stop motion produced and marketed by the Crawford Manufacturing Company of New Brunswick, New Jersey, whose commercial product is disclosed in general in a prior patent to Alfred Crawford, No. 1,992,860, dated February 26, 1935, while certain details of the device are disclosed in a prior patent to Michael Antonevich, No. 2,257,030, dated September 23, 1941, of which, in each instance, the Crawford Manufacturing Company is the assignee exclusively.

In each of the structures disclosed, respectively, in the aforesaid patents, the very uppermost part of the stop motion is in the form of a spider including a large central hub portion from which a number of arms radiate. In each instance, the outer end of the arm supports a thread controlled device which will operate to effect stopping of the knitting machine should the knitting thread or yarn become too tight, too loose, or break.

The thread controlled fingers of the entire series carried respectively by the radiating spider arms, operate a common control mechanism housed within the hub of the spider. Thus, in initial installation, it requires that a complete assembly of all the thread controlled mechanisms, including a switch operating element individual to each, and a switch actuating ring common to all, must be made before the device as a whole can be adjusted for operation with the knitting to which the stop motion is applied.

In the prior patent to Crawford, aforesaid, it will be noted that there is a second series of thread controlled switches housed in a hollow annular casing located above, but in relatively close proximity to the knitting head of the machine to which the stop motion is applied. These lower switches are subject to becoming fouled by lint, etc., entering through various openings in the annular casing, etc., through which certain elements of the device extend.

The present invention is directed to the provision of an improved type of switch structure adapted to replace both the top switches and the lower switches of the stop motion which as a whole is disclosed in the aforesaid Crawford patent. Primarily, the new switches are adapted to be completely enclosed in dust-proof casings to prevent entrance of lint and the fouling of the switch mechanism. Furthermore, the construction is such that the switches may be pre-assembled and adjusted individually and held in stock for future assembling or as replacements in the stop motions as a whole. The principles upon which both the top and bottom switches of the present invention are constructed are sub-

2

stantially the same, while the structures per se vary slightly.

In the accompanying drawings:

Fig. 1 is an outside side elevation of one of the lower switch units constructed to operate in accordance with the principles of the present invention;

Fig. 2 is an enlarged outside side elevation of the structure shown in Fig. 1, with the cover plate removed and the mechanism partly in section;

Fig. 3 is a transverse section taken on the line 3—3, Fig. 2;

Fig. 4 is a side elevation, partly in section, of the upper switch unit, with the cover plate removed;

Fig. 5 is a transverse section taken on the line 5—5, Fig. 4; and

Fig. 6 is a transverse section taken on the line 6—6, Fig. 4.

The new bottom switch, as shown in Figs. 1, 2, and 3 of the attached drawings, includes a dust-proof casing 1 in which is mounted a transverse shaft 2 having a sweep arm or feeler wire 4 secured to one end thereof outside the casing 1. The free end of the sweep wire 4 is provided with a thread eye 5 operating between fixed thread eyes 6, 6, through all three of which extends the knitting thread x on its way to the knitting head of the machine.

Within the casing 1 the shaft 2 is provided with a crank 7 which bears against a cam surface 8 on a long arm 9 of a bell crank lever which is pivoted at 10 within the casing 1. The short arm 11 of the bell crank lever has attached thereto one end of the tension spring 12, the opposite end of which is soldered or otherwise secured to a block 13 which is slidably mounted in the casing 1, and is adjustable by a screw 14 from outside the casing 1. Obviously by adjusting the screw 14 any desired degree of tension may be placed on the sweep arm 4, constantly tending to swing it in the direction of the arrow in Fig. 2, whereby more or less tension is applied to the thread x between the fixed guides 6, 6. Due to the relation between the long and short arms of the bell crank lever, very little axial extension of the spring 12 is required, and this provides uniform tension on the outer end of the sweep arm at all times through a rather long movement of the outer end of the sweep arm.

Should the yarn x break, or become excessively slack at or near the knitting head, the free end 5 of the sweep arm 4 will be released and the spring 12 acting through the bell-crank 11—9 will cause the cam face 8 of the long arm 9 to force the crank 7 downwardly, from its full line position shown in Fig. 2, to its broken line position shown in said figure, to permit the tip 9a

of the arm 9 to make electrical contact with a resilient contact 15.

The weight of the sweep arm 4 is substantially counterbalanced by an off-center weight 12a applied to the protruding end of the operating shaft 2, in order to make the action of the tension spring 12 more sensitive.

The contact 15 is secured by a shouldered rivet 16 to an insulating block 17, secured in the box 1 by a screw 18. The larger diametered portion 19 of the rivet 16 passes through an oversized hole 20 in the end wall of the box 1 and is connected by a screw 22 to an angle strap 21, which in turn is electrically connected to a buss bar 23 forming part of one side of the circuit for the electric knock-off mechanism (not shown) of the stop motion, the box 1, etc., being included in the second side of the circuit.

The boxes 1 are each provided with a slotted lug 24 adapted to be adjustably bolted to a supporting ring 25, similar to a corresponding ring of the Crawford patent aforesaid.

Obviously the switch mechanisms may be completely assembled in the boxes 1 and adjusted ready to be applied subsequently to the supporting ring 25 on machines having any prevailing number of yarn feeds, with one switch assembly for each feed. All the adjustment required, after the boxes 1 are in place, would be to bend the sweep wires 4 to bring the eye 5 in proper relation to the fixed eyes 6, 6.

The eyes 6, 6 are supported by arms 26, like the corresponding arms of the Crawford patent aforesaid, and these arms may be attached to covers 27 of the boxes 1 during remote assembly of the switch mechanisms therein, or the arms may be connected directly to the boxes 1 or to the supporting ring 25, as desired.

In the top switch shown in Figs. 4, 5, and 6 of the drawings, all of the mechanism is confined in the boxes 1a and these boxes are separately connected to the spider arms 116 of the aforesaid Crawford patent or the corresponding arms of the aforesaid Antonevich patent, thus eliminating the two coaxial shafts disclosed in said patents and which extend longitudinally of each spider arm; and also eliminating all of the switch mechanisms confined in the hubs from which the spider arms project.

These upper switch mechanisms are substantially the same as the lower switch mechanisms previously described as being confined in the boxes 1, and the same reference characters are here now employed. However, instead of the operating shaft, as the shaft 2 in the lower switch mechanism being parallel to the pivot 10 for the bell crank 9-11, the operating shaft 2a of the upper switch mechanism projects into the casing 1a through one end wall thereof, at right angles to the axis of the pivot 10a of the bell crank 9a-11a, therefore the long arm 9a is provided with a right angle extension 9b against which the crank 1a of the shaft 2a bears. The sweep arm 4a is normally urged in the direction of the arrow in Fig. 6 by a resiliently mounted arm 28, which corresponds to the same kind of arm as shown in the Antonevich patent aforesaid.

If the yarn x breaks or becomes excessively slack, the resiliently mounted arm 28 moves the sweep arm 4a upwardly turning the shaft 2a and crank 1a accordingly, permitting the right angular extension 9b of the long arm 9a of the bell crank 9a-11a under the influence of the spring 12 and weight 12a, to engage the resilient con-

tact 15a, closing the circuit between the buss bar 23a and the casing 1a to actuate the electric knock-off of the stop motion.

If the yarn should become excessively taut, the sweep arm 4a will be moved downwardly turning the shaft 2a and its crank 1a accordingly and forcing the right angular extension 9b of the bell crank 9a-11a into contact with a second resilient contact 15b which also closes the circuit for actuating the electric knock-off of the stop motion.

It will be understood that the feeler 4 or 4a, as the case may be, is extremely sensitive to fluctuations in the tension of the running yarn x. It also detects the presence or absence of a running yarn and in any instance of unnormal eventuality effects the proper reactions in the apparatus as a whole to stop the machine.

The bell-crank lever, which in effect constitutes a rotary switch element having one portion adapted to engage the electric terminal element 15 is extremely sensitive, and this sensitivity is maintained uniform by reason of the axis of the tension spring 12 being substantially tangent to the arc described by the point of attachment of the one end of the spring 12 with the short arm 11 of the bell-crank lever, due to the fact that such point travels but a very short distance and not sufficient to produce any substantial elongation of the spring 12.

I claim:

1. A switch structure for electric stop motions for knitting machines and the like, comprising a closed casing, an operating shaft pivoted in and having one portion projecting outside said casing, a bell-crank lever pivoted and confined within said casing, a tension spring operatively connected to one arm of said bell-crank lever and confined within said casing, an electric terminal element within said casing and engageable by a second arm of said bell-crank lever, a crank on the portion of the operating shaft disposed within said casing and engageable with one of said arms, and a thread engaging sweep arm secured to that portion of the operating shaft disposed outside said casing.

2. A structure according to claim 1, characterized by the bell-crank having a long arm and a short arm, with the tension spring connected to said short arm and the crank of the operating shaft engageable with said long arm.

3. A structure according to claim 1 characterized by the tension spring being partially opposed by an eccentric weight on the protruding portion of the operating shaft and partially counterbalancing the weight of the sweep arm, to make the tension spring more sensitive to fluctuations in the tension of the knitting yarn.

4. In a switch structure, the combination of a substantially fixed electric terminal element, a relatively rotatable switch element adapted to have one portion thereof engageable with said terminal element and comprising a bell-crank lever including a short arm and a relatively long arm, a tension spring operatively connected to said short arm with the axis of said spring substantially tangent to the arc of travel of the point of attachment of one end of the spring to said short arm to maintain the applied tension of said spring uniformly sensitive, and a feeler element engageable with and adapted to actuate said switch element into contact with said terminal element by overcoming said tension of said spring.

ALFRED CRAWFORD.
